UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FILLING-FEELER MECHANISM FOR LOOMS.

Application filed August 16, 1921. Serial No. 492,733.

To all whom it may concern:

Be it known that I, JONAS NORTHRUP, a citizen of the United States, residing at Hopedale, in the county of Worcester and 5 State of Massachusetts, have invented certain new and useful Improvements in Filling-Feeler Mechanism for Looms; and I do hereby declare the following to be a full, clear, and exact description of the invention, 10 such as will enable others skilled in the art to which it appertains to make and use the same.

The present invention relates to an improvement in filling feeler mechanisms for 15 looms.

In some forms of filling feeler mechanisms, a controller engages a portion of the shuttle. In the operation of the loom this causes wear upon the shuttle, and therefore 20 the more rapid consumption of shuttles. In other forms of filling feeler mechanisms a controller engages the surface of the bobbin spring. Now, the bobbin springs bear slightly 25 different positions in different shuttles, and this causes a different action of the feeler in the different shuttles. In other forms of filling feeler mechanisms, a controller contacts with the bobbin, and this is objectionable not only by reason of the wear on the bobbin, 30 but by reason of the fact that the bobbin is not always in precisely the same position owing to slight differences in the positions of the bobbin springs. In other forms of filling feeler mechanisms a special form of 35 front box plate was required to be used in order to adapt the loom for use with the feeler mechanisms. The substitution of a new box plate involved expense.

The object of the present invention is to 40 eliminate the wear of the controller on the shuttle, the uncertainties of engagement of the controller with the bobbin spring or bobbin, the reduction in size of the slot in the box plate, and the elimination of the necessity of providing new box plates. To these 45 ends the present invention consists in the improved filling feeler mechanism hereinafter described and particularly defined in the claims.

50 In the accompanying drawings illustrat-

ing the preferred form of the invention, Fig. 1 is a plan illustrating the mechanism; and Fig. 2 is a sectional elevation taken on the line 2—2, Fig. 1.

The illustrated embodiment of the invention is described as follows: The loom to which this filling feeler mechanism is applied may be of any usual or preferred construction in either a plain loom or a weft replenishing loom. If applied to a plain loom, the feeler mechanism operates to stop the loom upon critical exhaustion of the filling in the shuttle; and if applied to a weft replenishing loom, the feeler mechanism operates to bring about the insertion in the shuttle of a fresh supply of filling upon critical exhaustion. The portion of the loom shown in the drawing comprises a lay 1, a breast beam 2, a weft hammer 3, a shuttle box 4, a change shaft or stop shaft 5, a change or stop lever 6, all of which may be of the usual or any preferred construction. A knock-off bracket 10 attached to the breast beam projects outwardly from the loom frame and carries upon its end a filling feeler 11, substantially of the form shown in the Northrop Patent No. 1,249,280. The filling feeler is connected by means of a link 12 with the latch 13 pivoted at 14 upon the side of the controller arm 15, which is pivoted at 16 to the change or stop lever 6. The rear end of the controller arm 15 is turned down and rests upon the controller supporting plate 17 attached to the breast beam of the loom, upon the upper surface of which it is 75 adapted to slide back and forth. The controller arm 15 is provided with a slot 20 which receives the controller stud 21. This stud 21 is screwed into a hole in the forward end of the controller 22. The controller is 80 normally held in rearward position by the spring 23, which has its rear end attached to a pin 24 supported by the plate 25, secured to the controller plate 17. The rear end of the controller is adapted to engage a projection 30 on the rear box plate of the lay. On 85 every other beat of the lay, the controller is pushed forwardly in the slot in the controller arm, and upon each retreat of the lay following such forward movement of the controller 90

troller, it moves backward again under the influence of the springs 23. The controller latch 13 is provided with a downwardly extended lug 31 which is engaged by the controller stud 21 upon its rearward movement, thereby turning the latch 13 to the position shown in Fig. 1, and moving the latch out of the path of movement of the left-hand knife 32 of the weft hammer the spring 23 being 10 strong enough for this purpose. The controller spring 33 normally tends to move the latch 13 in a direction to bring its shoulder 34 in front of the weft hammer knife 32. When the feeler is prevented from turning 15 by engagement with filling on the bobbin, the release of the latch by the controller is ineffective to permit the spring 33 to swing the latch in front of the weft hammer knife 32. The weft hammer supports the controller, the latter resting upon a surface formed 20 on the weft hammer. The weft hammer moves forward and lifts the controller by engaging the cam surface 35 on the controller bunter, so that the controller is above the projection 30 on the box when the shuttle is 25 boxed on the right-hand side of the loom. But the weft hammer permits the controller to occupy the position shown in Fig. 2 when the shuttle is boxed at the left-hand side of 30 the loom, as shown in Fig. 1, so that the feeler is ineffective to cause weft replenishment or stoppage of the loom when the shuttle is boxed at the right-hand side of the loom.

35 The operation of the filling feeler mechanism is as follows: When critical exhaustion of the filling is reached, the spring 33 tends to swing the latch 13 in a direction to cause the feeler to move toward the butt of the 40 bobbin, and the tendency of the feeler so to move not being resisted by the presence of yarn on the bobbin, it swings with the latch, which moves in front of the knife 32 of the weft hammer and is pushed forward- 45 ly, thereby pushing the controller arm 15 forwardly and operating the change or stop shaft. The controller operates at each alternate beat of the lay to release the latch so as to permit it to swing under the influence 50 of its spring 33, if critical exhaustion of the yarn has been reached.

The controller is rectangular in cross-section, and is received in a straight-sided slot in the weft hammer. It is provided with 55 two cam surfaces 35 so that by lifting the controller bunter by hand it may be turned over, and by being screwed farther on or off of the stud it may be adjusted lengthwise on the stud, so that the time of the release of the latch by the controller may be nicely determined.

Having thus described the invention, what is claimed is:

1. A loom having, in combination, a lay 60 adapted to carry a shuttle, a shuttle box, a

filling feeler mechanism comprising a feeler, a latch, connections between the feeler and latch, means tending to move the feeler to cause its filling feeling end to move toward the butt of a bobbin in the shuttle, a controller for preventing such movement of the feeler, the shuttle box being provided with a part adapted to engage the controller, and thereby release the latch and feeler when the shuttle is boxed on the filling feeler side 75 of the loom.

2. A loom having, in combination, a lay 80 adapted to carry a shuttle, a box, a weft hammer, a filling feeler having a filling feeling end adapted to engage the filling on a bobbin in the shuttle, a latch, connections between the latch and the feeler, said latch having a part adapted to be engaged when in operative position by the weft hammer, a controller having provision for holding the 85 latch in inoperative position, means for moving the latch into operative position when the controller is actuated to release the latch lever.

3. A filling feeler mechanism for looms 90 having, in combination, a filling feeler, a latch, connections between the latch and filling feeler, a weft hammer, means tending to move the latch in a direction to present a portion to the action of the weft hammer, a controller having an end adapted to be struck by the lay, and a portion adapted to control the release of the latch, said controller having a cam surface which rests 95 upon the weft hammer, whereby, on alternate beats of the lay, the controller is lifted out of the range action of the lay.

4. A filling feeler mechanism for looms 100 having, in combination, a filling feeler, a latch, a weft hammer, a controller for controlling the operation of the latch, a controller actuating member on a moving part of the loom, said controller and weft hammer having cooperating cam surfaces adapted 105 to move the controller so as to thereby remove the controller from the field of action of its actuating member.

5. A filling feeler mechanism for looms 110 having, in combination, a lay provided with a shuttle box, a weft hammer, and a filling feeler mechanism comprising a filling feeler, a latch, a controller adapted to be engaged by the shuttle box on the forward beat of the lay, said weft hammer and controller having cooperating cam surfaces constructed 115 and arranged to move the controller out of the field of action of the shuttle box when the shuttle is not boxed on the filling feeler side of the loom.

6. A filling feeler mechanism for looms 120 having, in combination, a filling feeler, a latch, connections between the latch and filling feeler, a weft hammer, means tending to move the latch in a direction to present a portion to the action of the weft ham- 125

mer, a controller having an end adapted to be struck by the lay, and a portion adapted to control the release of the latch.

7. A filling feeler mechanism for looms having, in combination, a filling feeler, a controller for controlling the operation of the feeler, a controller actuating member

mounted on a moving part of the loom, and means to prevent the controller actuating member from actuating the controller when the shuttle is in the box on the opposite side of the loom from the feeler. 10

JONAS NORTHROP.
